UNITED STATES PATENT OFFICE.

WILLIAM J. McMILLAN, OF PHILADELPHIA, PENNSYLVANIA.

BOX-PARTITION-ASSEMBLING MACHINE.

1,311,609.

Specification of Letters Patent. Patented July 29, 1919.

Application filed October 7, 1918. Serial No. 257,205.

To all whom it may concern:

Be it known that I, WILLIAM J. McMILLAN, a citizen of the United States, residing in Philadelphia, Pennsylvania, have invented certain Improvements in Box-Partition-Assembling Machines, of which the following is a specification.

The object of my invention is to provide automatic means for assembling the members of a partition structure whereby the interior of a box or carton (hereinafter, for convenience, termed a box) is divided into separate cells, each for the reception of one of the articles for whose storage or trans-

portation the box is intended.

This object I attain in the manner herein-after set forth, reference being had to the accompanying drawing, in which,

Figure 1 is a longitudinal section of a box with the partition structure therein in accordance with my invention;

Fig. 2 is a transverse section of the same;

Fig. 3 is a perspective view of the partition structure detached from the box;

Fig. 4 is a longitudinal section of a machine made in accordance with my invention for assembling the members of said partition structure, and

Fig. 5 is a transverse section on the line 5—5, Fig. 4.

In Figs. 1 and 2 of the drawing, 1 represents a box having a partition structure made in accordance with my invention, and comprising a longitudinal member 3 extending from end to end of the box, and a series of transverse members 4, each extending from side to side of the box, said partition members overlapping or interlocking with one another and being, each provided, in

its interlocking portion, with a slot 6, the slots of the partition member 3 extending inwardly from the top of the same and the slot of each of the partition members 4 extending upwardly from the bottom, each of the slots of the member 3 receiving the un-slotted portion of one of the members 4 and the slots 6 of the latter receiving the corresponding unslotted portions of the member 3, as shown in Figs. 1 to 3.

The machine shown in Figs. 4 and 5 for automatically assembling the members 3 and 4 of the partition structure comprises two vertical reservoirs 8 and 9, the former receiving the members 3 which are disposed

flatwise one above another therein. The reservoir 9 has as many compartments as there are members 4 in each partition structure, said members being disposed edge to edge one above another in each compartment, as shown in Fig. 5, so as to be delivered one at a time, through a slotted guide 10 below the reservoir 9, onto a platform 11 below said guide.

The upper runs of a series of endless belts 12, disposed between the guide 10 and platform 11, receive from the reservoir 8, one at a time, the members 3 of the partition structure, so as to feed each of said members forwardly toward the series of members 4 as the latter drop from the reservoir 8 onto the platform 11. After each member 3 has been interlocked with the corresponding set of members 4, the assembled partition structure is carried forwardly beyond the line of the reservoir 9 so that it can be removed from the belts 12 and deposited in the box.

If desired, reciprocating slides may be substituted for the endless belts 12 without departure from the spirit of my invention.

I claim:

1. The combination, in a machine of the character described, of reservoirs for the members of the partition structure, one of said reservoirs having a series of compartments in each of which the members are disposed edgewise, one above another, the other reservoir having the members disposed flatwise one above another therein, and a conveyer for receiving the latter members in succession from their reservoir and feeding them into engagement with the other members as the latter are delivered from their reservoir.

2. The combination, in a machine of the character described, of a reservoir in which members are disposed edge to edge, one above another, a supporting platform for said members below each reservoir, a slotted guide for the members in their passage from the reservoir to said platform, a reservoir in which other members are disposed flatwise, and a conveyer whereby said latter members will be removed one at a time from their reservoir and carried to and interlocked with the first-named members.

In testimony whereof, I have signed my name to this specification.

WILLIAM J. McMILLAN.
